(Cl. D72—1)

To all whom it may concern:

Be it known that we, Svend Pedersen and Fred W. Neumeyer, residing at Chicago, in the county of Cook and State of Illinois, and Leo P. Helmey, residing at Clarendon Hills, in the county of Du Page and State of Illinois, all citizens of the United States, have invented a new, original, and ornamental Design for a Directional Signal for Motor Vehicles or the like, of which the following is a specification, reference being had to the accompanying drawing, forming a part thereof.

In the drawing:

Figure 1 is a view in front elevation of a directional signal for motor vehicles or the like, showing our new design;

Fig. 2 is a view in side elevation thereof, and

Fig. 3 is an end view thereof.

We claim:

The ornamental design for a directional signal for motor vehicles or the like, substantially as shown.

SVEND PEDERSEN,
FRED W. NEUMEYER,
LEO P. HELMEY.
